UNITED STATES PATENT OFFICE.

WILLIAM M. DUNCAN, OF ALTON, ILLINOIS.

FURNACE.

Application filed March 14, 1919. Serial No. 282,714.

To all whom it may concern:

Be it known that I, WILLIAM M. DUNCAN, a citizen of the United States of America, a resident of Alton, in the county of Madison, State of Illinois, have invented certain new and useful Improvements in Furnaces, of which the following is a full, clear, and exact description, reference being had to the accompanying drawings, forming a part of this specification.

My invention relates to improvements in furnaces and more particularly to a furnace provided with a traveling grate.

Prior to this invention endless chain grates have been used to carry fuel through the combustion chambers of furnaces, but such grates have been constructed and arranged to discharge the ashes at one end of the combustion zone on the grate. Owing to the limited area of the combustion zone on the ordinary traveling grate, all of the combustible constituents of the fuel are not consumed in the furnace, some of the carbon and other valuable fuel elements being discharged with the ashes at a point about midway of the length of the furnace. Another important problem involved in the use of the ordinary traveling chain grate lies in the difficulty of removing the ashes from the furnace. The most common practice is to form a deep ash pit under the middle portion of the furnace, where the ashes are discharged from the grate, and to use mechanical conveyers and blowers for the purpose of lifting the ashes and conveying them to the floor level at the front or rear of the furnace.

One of the principal objects of this invention is to increase the efficiency by providing a traveling grate on which substantially all of the fuel is consumed, and this is accomplished by retaining the fuel in the combustion chamber in such a manner that the elements which do not burn readily are ignited and consumed, instead of being prematurely discharged with the ashes.

A more important object is to entirely eliminate the expense of forming ash pits under the furnace, and to entirely eliminate the labor and expense of using special ash handling appliances for the purpose of elevating the ashes to the floor level.

Briefly stated, both of the foregoing objects are attained by the use of a fuel carrier and ash conveyor comprising an elongated traveling chain grate which may extend from a fuel intake at one end of the furnace to an ash outlet at the opposite end. About two-thirds or one-half of the top surface of the elongated traveling grate lies in the combustion chamber, and this two-thirds or one-half is preferably longer than the total length of an ordinary chain grate. This enables the fuel to be most effectively consumed in the combustion chamber. The remaining one-third or one-half of the elongated grate performs the function of an ash conveyor, and it enables the ashes to be delivered at a convenient point above the floor level without using special ash handling appliances. It will therefore be understood that the grate structure herein disclosed is something more than an extra long grate. It is a fuel carrier and ash conveyor; while the ordinary chain grate is not an "ash conveyor" in the sense that I use the term. The new grate structure actually conveys the ashes from the combustion zone to a distant discharge opening where the ashes are discharged above the floor level and at the exterior of the furnace. In addition to saving the labor and expense of excavating for ash pits and thereafter removing the ashes therefrom, the new structure can be most advantageously used in localities where it is not feasible to excavate below the furnace.

With the foregoing and other objects in view, the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Fig. I is a longitudinal section illustrating a furnace equipped with my combined fuel carrier and ash carrier.

Fig. II is a transverse section taken approximately on the line II—II, Fig. I.

Fig. III is a transverse section on line III—III, Fig. I.

Fig. IV is a detail view of the ash receiving pocket at the rear of the furnace.

To illustrate the invention I have shown a furnace provided with front and rear walls 1 and 2 on which a boiler 3 is mounted, the boiler and furnace being approxi-

100

105

110

mately equal in length. A fuel intake 4 is formed in the front wall, and an ash outlet 5 is formed in the rear wall.

5 A designates a fuel carrier and ash conveyor in the form of an endless elongated traveling chain grate passing through the intake 4 and outlet 5, said chain grate being mounted on wheels 6 and 7 at the exterior of the furnace. The wheels 6 in front of the furnace may be idle wheels, and the wheels 7 at the rear of the furnace may be fixed to a power shaft 8 which may be rotated by any suitable mechanism. A coal hopper 9 is located in front of the fuel intake 4 to provide for the delivery of fuel to the grate.

10 The traveling grate is inclined upwardly from the fuel intake 4 to the ash outlet 5, so that the ashes will be discharged at a relatively high elevation. A hood or housing 10 may be placed around the discharge end of the grate, so as to form an ash compartment above the floor level.

15 B designates an elongated shield located in the rear portion of the furnace for the purpose of protecting the ash conveying portion of the grate from the intense heat in the combustion chamber. This shield B lies above and adjacent to the grate, so as to provide a restricted ash passageway leading from the combustion zone to the ash outlet 5. Smoke and gaseous products of combustion are conducted downwardly at the rear of the furnace, through a smoke passageway 12. The combustion zone for solid fuel on the grate extends from the fuel intake 4 to the shield B and this zone is extra long so maximum efficiency may be obtained by consuming all of the combustible material in the fuel. The combustible gases rising from the solid fuel are consumed at all points between the boiler and the combined fuel carrier and ash conveyor. It is therefore very hot in the combustion chamber above the ash conveying portion of the endless grate, and since the relatively thin bed of ashes would not effectively protect this portion of the grate, I prefer to use the shield B to prevent injurious overheating or burning of the ash carrying portion of the apparatus. This shield comprises fireproof blocks 13 supported on metal T-bars 14.

20 In the combustion zone for solid fuel, the grate is cooled by air currents passing through draft boxes 15, each of said draft boxes being open at one end to receive a forced draft and open at the top to deliver the air currents through the fuel supporting portion of the grate.

25 An ash-catching table C, formed by a number of metal plates or sheets 16, is arranged below but adjacent to the bottom face of the ash conveying portion of the grate. A very narrow ash passageway is thus formed from the rearmost draft box

15 to the ash outlet 5. The grate itself will serve as a sweep for moving the ashes along the ash-catching table C. This table also prevents the admission of air from the open lower portion of the furnace to the ash conveying portion of the grate. 70

17 designates a U-shaped ash-receiving pocket located at the rear of the furnace, beyond the ash outlet 5, and forming a continuation of the ash-catching table C. The pocket 17 and table C are surrounded by the endless grate, and the pocket is open at the top to receive the ashes discharged at the rear end of table C. This pocket is also open at its ends to permit the ashes to drop into the ash compartment 10 without striking the lower portion of the endless grate structure. 75

20 The upper portions of the elongated chain grate support a long bed of fuel and a long bed of ashes. Since these upper portions are driven for a considerable distance while subjected to the weight of the fuel and ashes, I preferably utilize tracks and rollers to support the same. The chain grate consists of several endless chains formed by endless rows of grate links connected by pivot rods 18, and anti-friction rollers 19 are rotatably mounted on these pivot rods at points between adjacent grate links. Tracks 20, 25 surrounded by the endless grate, extend from the fuel intake 4 to the ash outlet 5, said tracks being located below but adjacent to the upper course of the traveling grate. The rollers 19 extend slightly below the upper grate links and they travel on the tracks 20. In the combustion zone, above the draft boxes 15, the bottom faces of the grate bars engage or lie very close to transverse separating bars 25 between the draft bars, thereby preventing free escape of the draft from one draft box to the zone over another draft box. At the rear portion of the furnace, immediately below the ash-conveying portion of the grate, the tracks 20 lie between and form supports for the ash-catching plates 16, as seen in Fig. II. 100

25 At the lower portion of the long endless grate structure, the grate links are inverted, with their fuel-receiving faces exposed at the bottom of the structure, and continuous friction tracks 21 are arranged below said lower portion and engaged by said fuel-receiving surfaces to form long friction slides on which the lower grate links are supported. Prior to this invention, it has been customary to cause the lower returning portion of the grate to travel over transverse rollers as it moves toward the fuel intake, the rollers being mounted at fixed points below the grate structure. In actual practice I have found that a link will occasionally break and hang from its pivot rods, with the result of striking the rollers below the grate, thereby causing serious injury to 105 110 115 120 125 130

the traveling grate structure. However, in accordance with the present invention, if the long tracks 21 are used with unobstructed spaces between them, a broken link would 5 travel freely over a continuous track or hang freely in an unobstructed space between two tracks, until it eventually reaches one end of the structure, where it can be readily observed and repaired by the operator.

10 I claim:

1. A furnace having a fuel intake, an ash outlet and a combustion chamber between said intake and outlet, a fuel carrier and ash conveyor comprising an elongated traveling grate having a fuel supporting portion in the combustion chamber and an ash conveying portion extending from said combustion chamber to convey the ashes to 15 said outlet, a shield arranged over the ash conveying portion of the grate to protect said portion from the heat of the combustion chamber, and an ash-catching plate arranged immediately below said ash conveying portion 20 of the grate, said shield and ash-catching plate being extended from the combustion chamber to said ash outlet.

2. A furnace having a fuel intake, an ash outlet and a combustion chamber between 25 said intake and outlet, a fuel carrier and ash conveyor comprising an elongated traveling grate having a fuel supporting portion in the combustion chamber and an ash conveying portion extending from said combustion chamber to convey the ashes to said outlet, an ash catcher arranged below said ash conveying portion, said ash catcher being immediately adjacent to the bottom face 30 of the traveling grate to provide a narrow ash passageway below and longitudinally of the grate, so that the grate will serve as a sweep for moving the ashes along said ash catcher and toward said outlet, and an ash-receiving pocket arranged to receive 35 ashes from said ash passageway.

3. A furnace having a fuel intake, an ash outlet and a combustion chamber between 40 said intake and outlet, a fuel carrier and ash conveyor comprising an elongated traveling grate having a fuel supporting portion in the combustion chamber and an ash con-

veying portion extending from said combustion chamber to convey the ashes to said outlet, an ash catcher arranged below said ash conveying portion, said ash catcher being immediately adjacent to the bottom face 45 of the traveling grate to provide a narrow ash passageway below the grate, so that the grate will serve as a sweep for moving the ashes along said ash passageway and toward said outlet, and an ash-receiving pocket arranged to receive ashes from said ash passageway, said ash-receiving pocket being open at the top to receive the ashes 50 discharged from said ash passageway and said pocket being open at one side of the grate to discharge the ashes.

4. A furnace having a fuel intake, an ash outlet and a combustion chamber between 55 said intake and outlet, a fuel carrier and ash conveyor comprising an elongated traveling grate having a fuel supporting portion in the combustion chamber and an ash conveying portion extending from said combustion chamber to convey the ashes to said 60 outlet, a shield arranged over the ash conveying portion of the grate to protect said portion from the heat of the combustion chamber, and an ash-catching plate arranged immediately below and separated from said 65 ash conveying portion of the grate to provide an ash passageway below said shield and ash conveying portion.

5. A furnace having a fuel intake in its 70 front wall, an ash outlet formed transversely of its rear wall, and a combustion chamber adjacent to said fuel intake, a fuel carrier and ash conveyor comprising an elongated traveling grate extending from said fuel intake to said ash outlet, and a shield arranged over said elongated traveling grate and extending from said combustion chamber to the ash outlet in said rear wall, said elongated traveling grate having a fuel supporting portion in said combustion chamber 75 and an ash conveying portion located below said shield and extending from said combustion chamber and entirely through the ash outlet in the rear wall.

In testimony that I claim the foregoing I hereunto affix my signature.

WILLIAM M. DUNCAN.
